R. WARD.
STEAM RADIATOR.
APPLICATION FILED MAR. 23, 1908.

916,640.

Patented Mar. 30, 1909.

UNITED STATES PATENT OFFICE.

ROBERT WARG, OF MILWAUKEE, WISCONSIN.

STEAM-RADIATOR.

No. 916,640

Specification of Letters Patent.

Patented March 30, 1909.

Application filed March 23, 1908. Serial No. 422,758.

To all whom it may concern:

Be it known that I, ROBERT WARG, a citizen of the United States, and resident of Milwaukee, in the county of Milwaukee and State of Wisconsin, have invented certain new and useful Improvements in Steam-Radiators; and I do hereby declare that the following is a full, clear, and exact description thereof.

10 The object of my invention is to prevent "air-pockets" in steam radiators, and to also dispense with the necessity of maintaining a constant steam pressure in order to insure proper circulation.

15 The invention therefore consists in various details of construction and combination of parts as hereinafter set forth with reference to the accompanying drawings and subsequently claimed.

20 In the drawings: Figure 1 represents an elevation of a steam-radiator embodying the features of my invention, the view being partly broken away and in section, as indicated by line 1—1 of Fig. 2, and Fig. 2, a 25 sectional plan view of the same with parts broken away and parts in section, as indicated by line 2—2 of the preceding figure.

Referring by numerals to the drawings, 1 indicates a cast hollow radiator-base, which 30 base is formed with transverse end-heads 2 and 2^a respectively. The heads communicate with chambers 3, 4, that are separated by a division wall 5, the base bottom 6 of each chamber being inclined from the division- 35 wall toward the heads to insure perfect drainage of condensation. The upper wall 7 of the chambers is provided with series of rows of tapped apertures grouped upon either side of the division wall 5. Into 40 these apertures are fitted the ends of looped steam-pipes 8, the same being nested in rows with their vertical legs upon opposite sides of said division wall 5, whereby steam is circulated from one chamber to the other.

45 As shown in Fig. 2 of the drawings, two or more radiator bases with their looped pipes are preferably coupled together to constitute a complete radiator, although one section may be used with the same results 50 where a small area of radiator surface is sufficient. With this in view the heads of each radiator base are provided with single transverse openings 9 and 10 respectively upon opposite sides, the openings constituting right and left steam inlet and discharge communication to the chambers. By

the above construction it is apparent that any number of the radiator bases may be assembled in a battery in such relation that steam admitted to the first base, through 60 its outside opening 9 will be compelled to pass from the adjacent chamber 9 through the looped pipes in the opposite chamber, and from there directly into the next radiator base by way of the communicating 65 openings in the heads and so on until the steam has finally completed the circuit in a continuous zig-zag course through the entire battery. By this arrangement it will be seen that the steam passes directly through 70 the radiator forcing the air ahead, the condensation being shed into the heads from which it is drained by drip-pipe 16.

In assembling the sections, the radiating base-heads having communicating openings 75 are preferably provided with metallic packing rings 11, which rings are interposed between the adjacent faced edges of the openings. The opposite ends of said radiator bases have closed abutting heads, between 80 which heads are placed suitable rings 12, which serve as spacers. The outer or exposed head-ends of the assembled bases are each provided with cap-plates 13 having apertures for clamping bolts 14, which bolts 85 in connection with their nuts serve to draw the several sections together and maintain steam-tight connection therebetween.

The steam-inlet and discharge openings of 90 the first and last sections of the radiator base have their cap-plates provided with threaded apertured openings 15 for the reception of steam-inlet and discharge pipes, the latter being either connected to another radiator or open direct to the atmosphere. 95

From the foregoing description it will be understood, should the heating system be supplied by exhaust steam there would be no back-pressure upon the engine supplying the exhaust, which exhaust would be freely discharged from the last radiator to atmosphere. If live-steam is utilized any well known method of connection from the last radiator may be employed. Under either of these arrangements great efficiency and 100 economy in heating is effected, while at the same time liability of the formation of air-pockets in the pipes is eliminated, this result being due to the direct flow of steam.

Where it is desired to carry steam-pressure 110 in the system, the last radiator is provided with a closed discharge-end and a suitable

air-vent valve in order to dispel air from said system.

I claim:

A steam radiator having a plurality of 5 parallel sections, each of which sections comprises a longitudinal hollow base having a central transverse division-wall therein, whereby separate chambers are formed, the bottom-wall of each chamber of each base- 10 section being inclined in opposite directions from its division-wall, said hollow base being formed with a transverse head in direct communication with the chambers of each of said base-sections and each of said heads

being provided with openings communicat- 15 ing with the heads of adjacent parallel sections at alternate opposite ends of said sections, and a series of looped pipes for each section, each series being connected to a section upon opposite sides of its division-wall. 20

In testimony that I claim the foregoing I have hereunto set my hand at Milwaukee, in the county of Milwaukee and State of Wisconsin in the presence of two witnesses.

ROBERT WARG.

Witnesses:

GEORGE FELBER,
N. E. OLIPHANT.
